CLAIM

The ornamental design for a plant fill light, as shown and described.

DESCRIPTION

FIG. 1 is a top, front and left side perspective view of a plant fill light showing our new design;

FIG. 2 is a top, rear and right side perspective view thereof;

FIG. 3 is a bottom, front and right side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of portion 10 in FIG. 1;

FIG. 11 is an enlarged view of portion 11 in FIG. 2;

FIG. 12 is an enlarged view of portion 12 in FIG. 3;

FIG. 13 is a perspective view showing the plant fill light in a disassembled state;

FIG. 14 is an enlarged view of portion 14 in FIG. 13;

FIG. 15 is another perspective view showing the plant fill light in a disassembled state; and,

FIG. 16 is an enlarged view of portion 16 in FIG. 15.

The broken lines in the drawings illustrate portions of the plant fill light which form no part of the claimed design.

1 Claim, 16 Drawing Sheets
